CLAIM

The ornamental design for an archery stabilizer, as shown and described.

DESCRIPTION

FIG. 1 is a front, top and right perspective view of the inventive design.

FIG. 2 is a front view of the inventive design. The design is symmetrical with the back, left and right sides identical to the front view.

FIG. 3 is a top view of the inventive design; and,
FIG. 4 is a bottom view of the inventive design.

The broken lines in the drawings are used to illustrate unclaimed portions in the form of optional weights for the archery stabilizer and form no part of the claimed design.
